UNITED STATES PATENT OFFICE.

MASUTARO KAIZUMI, OF SEATTLE, WASHINGTON.

SHOE.

1,277,941.

Specification of Letters Patent. Patented Sept. 3, 1918.

Application filed September 6, 1917. Serial No. 190,036.

To all whom it may concern:

Be it known that I, MASUTARO KAIZUMI, a subject of the Emperor of Japan, residing at 152 9th avenue, Seattle, in the county of 5 King and State of Washington, have invented certain new and useful Improvements in Shoes; and I do hereby declare the following to be a full, clear, and exact description of the invention, such as will enable 10 others skilled in the art to which it appertains to make and use the same.

This invention relates to improvements in shoes, and particularly to shoes with removable and interchangeable heels.

15 It is an object of the invention to provide heels and shoes so constructed that when edges of the heels on a shoe have been worn off from a side of the heel section that the section may be taken off and changed to the 20 opposite shoe, and the worn heel from the other interchanged with the first one, thereby securing greater wear from the heels, and also preventing the shoes from "running over" to the sides.

25 The invention further provides for the ready and rapid interchange of heels by the wearer thereof, without any special tools therefor, and provides for the efficient locking of the heel when in place.

30 The invention consists in the construction, the organization and in details more fully described hereinafter, one embodiment of the invention being shown in the accompanying drawing in which.

35 Figure 1 represents a shoe with a heel in place, with the front portion of the shoe turned up, and showing in dotted lines, the normal position of the shoe;

40 Fig. 2, represents a front view of the heel section assembled and locked with connecting key and pins;

Fig. 3, is a bottom plane of the upper section of the heel.

Like numerals on the several figures represent like parts, the upper of the shoe is designated at 1. 2 is the removable section of the heel made in any number of lifts of leather or other suitable material held together with nails or other means as N. An 45 upper section 2' of the heel is securely fixed to a shoe sole 3 by nails N or otherwise, both 50

the upper and lower sections 2 and 2' having longitudinal keyways in their opposing faces cut out wider in the bases of such keyways to form holding shoulders 2^a and 2^b. The 55 keyways shown are of dovetail shape and do not extend the full length of the heel, so that the heel has the usual appearance. A key 4 made of wood or other suitable material is constructed with a shape or form 60 to fill the two opposed keyways in sections 2 and 2'; and when driven into the keyways from the breast of the heel the two sections 2 and 2' are held securely against each other, so that the heel as completed resembles any 65 ordinary shoe heel.

Section 2 carries a plurality of dowel pins 5, 5, and section 2' is provided with holes 6 into which the pins fit, and these prevent the sections working out of proper alignment.

70 The shoe sole 3, in Fig. 1, is turned up leaving clearance space so that the key can be inserted into the keyway in 2', as the bottom of the sole, as here shown forms the 75 top of this keyway. When down in line of normal position for use, shown in Fig. 1 by dotted line, pressure may be applied to the outer front end of the key by the adjacent position of the sole and so prevents the key 80 from working loose until the wearer desires to remove the same, when the sole is turned up and the key removed, whereupon the outer section 2 readily drops off or is removed by inserting a blade and lifting the 85 same off of the dowel pins or the key can be driven in and friction will hold it in place. Any knife blade will be sufficient to remove the parts when desired.

90 The line of wear, common to many people, is shown at W and this wear causes the shoe to run over. By simply changing the heels at various times the shoes can be maintained in better shape and much additional wear secured.

95 What I claim as new is:

1. A shoe comprising an upper, a slotted heel lift secured thereto, a slotted removable heel section doweled to the lift, and a key slidably fitting the slots and interlocking said lift and section, said key having 100 recessed sides.

2. A shoe comprising an upper, a dove-tail key attachable thereto, and a removable heel section secured to the shoe by said key and means for holding the section in alignment to the shoe.
3. In combination a shoe, heel sections having opposed undercut keyways, means for alining said sections, and a key fitting said ways to secure said sections together.

4. In combination a shoe, heel sections 10 having opposed dove-tail keyways, means for alining said sections, and a double dove-tail key to secure said sections together, the key frictionally fitting between the bottom section and the sole of the shoe.

15 In testimony whereof I affix my signature.

MASUTARO KAIZUMI.
